UNITED STATES PATENT OFFICE.

NETTIE A. M. SANDS, OF NEWARK, NEW JERSEY.

HEAD-COVERING.

946,770.

Specification of Letters Patent. Patented Jan. 18, 1910.

Application filed August 26, 1909. Serial No. 514,814.

To all whom it may concern:

Be it known that I, NETTIE A. M. SANDS, a citizen of the United States of America, residing at Newark, in the county of Essex 5 and State of New Jersey, have invented a new and useful Head-Covering, of which the following is a specification.

The object of the invention is to provide a head-covering of tasteful and inexpensive 10 construction, which is readily adjustable to any size of head and to any manner of wearing the hair.

A further object is to provide the head-covering with a detachable vizor and a cape, 15 and to render it serviceable for either indoor or out-door wear, or in bathing, as a protection against dust, sun, wind and rain, and as a hat-protector in stormy weather.

In the accompanying sheet of drawings 20 which forms a part of this application— Figure 1 is a perspective of a head-covering embodying my invention, as applied. Fig. 2 is a plan of the vizor from above. Fig. 3 is a view of the body portion from 25 underneath. Fig. 4 is a plan of the cape viewed from the outer side.

The head-covering comprises a body-portion 1 of a single piece of pliable material, as soft silk, cut in substantially a circle, with 30 a hem running around its periphery. About one-third of the periphery 2 is permanently gathered. The balance of the periphery 3 is provided with a gathering cord 4 by which the covering can be gathered up under 35 the hair. A ring 5 is provided through which the fabric at the middle of the body-portion can be drawn to take up any fullness. This ring may be sewed to the fabric, one side of the ring only being connected 40 so as to prevent it from being lost and not interfere with the drawing of the fabric therethrough. The permanently gathered portion of the periphery of the body-portion is adapted for the attachment thereto 45 of a vizor 6 when desired, this portion of the periphery and the meeting edge of the vizor being provided with similarly spaced mating clasp-buttons 7. The remainder of the periphery, which has the gathering cord, 50 is also provided with clasp-buttons 8 with which may be engaged the mating parts of the buttons along one edge of a cape 9 when

it is desired to attach the cape. The opposite edge of the cape is provided with a gathering cord 10 and the ends of the cape are 55 provided with mating clasp-buttons 11. Both the gathering cord of the cape and these buttons enable the cape to be drawn about the neck and fastened under the chin.

What I claim as new, and desire to secure 60 by Letters Patent of the United States, is—

1. In a head or hat covering, the combination of a body-portion of pliable material, and a ring through which the central portion of the body-portion is gathered, substantially as described.

2. In a head or hat covering, the combination of a vizor, a gathering cord, and a body-portion formed of a flat substantially circular piece of pliable material having a 70 portion of its periphery permanently gathered and provided with button connections for the vizor and the balance of the periphery hemmed to receive the gathering cord, substantially as described.

3. In a head or hat covering, the combination of a vizor, a gathering cord, a cape, and a body-portion formed of a flat substantially circular piece of pliable material having a portion of its periphery permanently gathered and provided with button connections for the vizor and the balance 80 of the periphery hemmed to receive the gathering cord and provided with button connections for the cape, substantially as described.

4. In a head or hat covering, the combination of a vizor, a gathering cord, a cape, a body-portion formed of a flat substantially circular piece of pliable material having a portion of its periphery permanently gathered and provided with button connections for the vizor and the balance of the periphery hemmed to receive the gathering cord and provided with button connections 90 for the cape, and a ring through which the central portion of the body-portion is gathered, substantially as described.

Signed at New York, borough of Manhattan, N. Y., this 24th day of August, 1909. 100

NETTIE A. M. SANDS.
